Denver, Colo.

Application July 26, 1954, Serial No. 445,668

6 Claims. (Cl. 5—111)

This invention relates to a bouncing acrobatic table of the type known as a trampoline, and has for its principal object the provision of a trampoline which can be quickly and easily folded and mounted for transportation through restricted spaces, such as doorways and the like.

Another object is to so construct the trampoline that the supporting leg structures will act as diagonal brace structures so that all transverse members below the bed or webbing which might be injurious can be eliminated.

A further object is to provide a trampoline in which the supporting legs will automatically fold against the trampoline sections when the latter are folded together, and to provide portable wheeled supports for transporting the trampoline, and protective aprons for concealing and preventing accidental contacts with the trampoline springs.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawing:

Fig. 1 is a plan view of the improved trampoline, partially broken away to illustrate the supporting structure;

Fig. 2 is a side view thereof in the erected position;

Fig. 3 is an enlarged, fragmentary, diagonal view, looking along the arrow 3 in Fig. 1;

Fig. 4 is a similar enlarged, fragmentary view, looking along the arrow 4 in Fig. 1;

Fig. 5 is a detail cross-section through the edge of the trampoline bed, taken on the line 5—5, Fig. 1;

Fig. 6 is a similar detail section, taken on the line 6—6, Fig. 1 showing a detail view of a protective apron-supporting structure employed upon the improved trampoline;

Fig. 7 is an enlarged, fragmentary, side view, illustrating a type of hinge employed in the improved trampoline;

Fig. 8 is a similarly enlarged, detail section, taken on the line 8—8, Fig. 7;

Fig. 9 is a detail, perspective view on the scale of Fig. 1, illustrating a wheeled standard employed for transporting the improved trampoline;

Fig. 10 is a side view of the improved trampoline as it would appear while being folded for transportation; and

Fig. 11 is an end view of the improved trampoline in the folded, transportation position.

The table portions of modern trampolines are formed from a plurality of longitudinally and laterally extending webbings stitched together to form a flexible bed bottom, which will be herein designated as the "bed." Other types are formed with a single sheet of flexible canvas or the like.

This improved trampoline is designed for use with either type of bed, and for convenience of illustration, is illustrated as a single flexible sheet which will be herein designated as the bed 12. The flexible bed 12 is resiliently supported in a taut, stretched condition by means of a

2

plurality of peripheral tension springs 13 extending to a supporting framework. It is in the supporting framework that the principal advantages of this invention reside.

The framework of this improved trampoline comprises two tubular, U-shaped end members 14 and two straight, tubular side members 15. The side members 15 extend between the terminals of the two U-shaped end members 14 to form a rectangular, elongated enclosing frame with four rounded corners.

10 The side members 15 are joined to the extremities of the U-shaped end members 14 by means of elongated, channel-shaped hinge members 16, the extremities of which extend on opposite sides of the adjacent extremities of the frame members 14 and 15 and are hingedly secured to the latter by means of spaced-apart hinge rivets or pins 17. The hinge members 16 extend across the tops of the joints between the members 14 and 15 and the tops of the hinge members are notched back, as indicated at 18, to provide space to allow the frame members 14 and 15 to swing into parallel relation, such as indicated in broken line at "A" in Fig. 10.

The tension springs 13 are secured at their inner extremities in any desired manner to the flexible bed 12. They are hooked at their outer extremities through 25 perforated attachment ribs 19 which are welded or otherwise secured to, or formed on, the inside faces of the straight portions of the frame members 14 and 15.

Each of the straight side members 15 is trussed against vertical stresses by means of a truss rod 20 which is welded 30 to the extremities of each member 15 at its extremities, and which is medially spaced from the member 15 by means of a horizontal tubular axle sleeve 21.

The transverse portions of each of the U-shaped frame members 14 is strengthened and stiffened against horizontal stresses by means of a truss member 22 welded at its extremities to the member 14 and spaced medially therefrom by means of a suitable spacer 22'.

40 The supporting frame is supported upon four diagonally positioned, V-shaped, leg frames 23. Each leg frame comprises a tubular, trussed frame having a rounded bottom portion covered by means of a cushion sleeve 24 of rubberized fabric or other suitable material to prevent slippage upon and damage to a floor. The upper extremities of each V-shaped leg frame extend horizontally and 45 oppositely outward to form hinge stubs 25.

The hinge stubs 25 are rotatably received in hinge collars 26, there being one hinge collar 26 welded beneath each extremity of each of the U-shaped frames 14, and two hinge sleeves welded in spaced relation beneath the mid-portion of each of the U-shaped frames 14 in aligned pairs so that the leg frames will extend diagonally across the corners of the U-shaped frames 14 approximately below the corners of the flexible bed 12.

50 The leg frames are prevented from swinging outwardly by means of flexible chains 27 extending from the truss rods 20 at each side to the leg frames 23.

The leg frames are prevented from swinging inwardly by means of tubular diagonal braces 28. Each brace has an angularly turned, horizontal upper end portion 29 60 adapted to be received in a receiving sleeve 30 welded beneath the arcuate corner of the U-shaped frame 14. Each diagonal brace 28 is also provided with an angularly turned, horizontal, lower end portion 31 which is rotatably received in a bearing tube 32 welded or otherwise secured to the leg frame 23. Each diagonal brace is resiliently held in position in its sleeve 30 and in its bearing tube 32 by means of a tension spring 33 tensioned between the brace 28 and the leg frame 23.

65 It can be seen that if a weight or other impact is imposed upon the medial portion of the flexible bed 12, it will tend to pull the two side frame members 15 inwardly toward each other. In the usual trampoline this inward

pull is resisted by cross members below the bed which limit the depression of the latter and which are dangerous to users of the trampolin.

In this improved trampolin, this inward pull of the side members is transmitted to the ends of the two U-shaped frame members, tending to pull the latter inwardly. The inward pull on the extremities of the U-shaped frame members is resisted first by the natural resistance of the members themselves, and second by the diagonal placement of the leg frames 23, which serve as rigid diagonal braces for the extremities of the U-shaped frame members, and which act to transmit the inward moment to the mid-portion of each end frame member. The latter are prevented from bending under the resulting stress by the truss member 22.

Two of the wheeled standards, as illustrated in Fig. 9, are employed for transporting the trampolin. Each of the wheeled standards comprises a horizontal base tube 34 supported at its extremities upon caster wheels 35. A vertical post or standard 36 is secured to and arises from each base tube 34. The upper extremity of each post or standard terminates in a horizontally projecting bearing stud 37. A hooked arm 38 projects from one side of the upper portion of each post or standard 36, and a U-shaped receiving yoke 39 projects from the other side of the lower portion thereof.

Let us assume that it is desired to fold the trampolin from the erected position of Figs. 1 and 2 and transport it to a new location. The sides of the trampolin are alternately, slightly lifted and the bearing studs 37 of the posts or standards 36 are slipped into the bearing sleeves 21 of the side frame members. The height of the posts or standards 36 is such that when the studs 37 are slipped into the sleeves 21, the bed will be elevated above its working position.

The end portions 29 of the diagonal braces 28 are pulled from the receiving sleeves 30 against the action of the springs 33 to release the leg frames. The U-shaped end frame 14 at the right is lifted upwardly, as indicated in solid line at "B" in Fig. 10. As it moves upwardly, it will increase the tension in the two chains 27 at that extremity. As the tension increases, the chains will act to pull the two leg frames 23 into tight, parallel, folded position on the end member 14. The folding is continued until the end member 14 and its associated leg frames lie in the folded position as indicated at "A" in Fig. 10.

The U-shaped end member 14 at the left extremity is now similarly folded upwardly and folded over the top of the folded right end frame so that the two end frames and their associated leg frames will lie in horizontal, parallel relation upon the side frame members 15, supported on the posts 36. The folded structure is now tilted to the right to a vertical position about the axes of the sleeves 21 so that the side frame structures will enter into the U-shaped yokes 39 to prevent withdrawal of the bearing studs 37 and to support the entire trampolin in a vertical position between the posts or standards 36 with the weight being carried upon the four caster wheels 35. The down-folded left end frame depends from its hinge member over the up-folded right end frame to prevent the latter from unfolding. The height of the folded structure is only slightly in excess of the length of the side members 15 and the width is exceedingly narrow so that it can be conveniently wheeled through doorways and other restricted spaces.

When it is desired to unfold the trampolin for use, the folded structure is swung upwardly until it strikes the hook arms 38, which serve as a stop. The left end frame is then unfolded, while the hook arms prevent the remainder from tilting. The right end frame is then unfolded, the diagonal braces are engaged, and the posts or standards 36 are removed. The trampolin is now ready for use.

Accidents occasionally occur on trampolin due to the legs and arms of the users dropping between the springs.

This is avoided in the improved trampolin by providing flexible aprons 40 along the two sides and the two ends of the bed 12. These aprons are supported above the springs 13 upon resilient supporting rods 41, the outer extremities of which are turned vertically downward and inserted through openings in the frame members 14 and 15. The outer edges of the aprons are tied to the frame members by suitable tying tapes 42. The inner edges are supported on the inner extremities of the rods 41 and are tensioned longitudinally by means of end springs 43. This supports the aprons above the springs 13 so that they do not slap and vibrate against the springs. The aprons however, are sufficiently resilient to prevent injury to a body falling thereon, and are sufficiently tensioned to prevent the arms or legs of the user from being forced between the springs. Since these aprons are completely flexible, they fold with the folding of the bed.

While a specific form of the improvement has been described and illustrated herein, it is to be understood that the same may be varied, within the scope of the appended claims, without departing from the spirit of the invention.

Having thus described the invention, what is claimed and desired secured by Letters Patent is:

1. A trampolin comprising: an elongated, flexible bed; a side frame member extending along the medial portion of each side of said bed; a U-shaped frame member extending across each end of said bed to the corners thereof thence extending inwardly from said corners along the opposite sides of the extremities of said bed toward said side frame members; an elongated hinge link connecting each extremity of each U-shaped frame member to the adjacent extremity of one of said side frame members; tension springs secured to and extending between said bed and said frame members; four V-shaped leg frames, there being one of said V-shaped leg frames positioned below and extending diagonally across each corner of each U-shaped frame member; hinge means securing the extremities of each of said V-shaped frames to the adjacent U-shaped frame member, and flexible tension members, each secured at one end to an intermediate point of an adjacent side frame member and at the other end to said leg frame to retain said leg frames from spreading when set up.
2. A trampolin as described in claim 1 in which the hinge means at one extremity of each V-shaped leg member is positioned adjacent the extremity of one of said U-shaped frame members and the hinge means at the other extremity of the V-shaped leg member is positioned adjacent the middle of the U-shaped frame member; and a rigid, detachable brace member extending from each leg frame upwardly and outwardly to the adjacent corner of a U-shaped frame member.
3. A trampolin as described in claim 2 having a truss member mounted on the mid-portion of each U-shaped frame member resisting flexure of the latter in the plane of said bed; and an additional truss member mounted on each of said straight portions of said side frame members resisting vertical flexure thereof.
4. A trampolin as described in claim 3 having a bearing sleeve mounted at the middle of each side frame member in axial alignment with each other; two supporting posts; a stud projecting from each post, said studs adapted to be received in said bearing sleeves to rotatably support said frame members and said bed; and wheels supporting each post.

5. A trampolin comprising: an elongated, flexible bed; a side frame member extending along the medial portion of each side of said bed; a U-shaped frame member extending across each end of said bed to the corners thereof thence extending inwardly from said corners along the opposite sides of the extremities of said bed toward said side frame members; an elongated hinge link connecting each extremity of each U-shaped frame member to the adjacent extremity of one of said side frame members;

tension springs secured to and extending between said bed and said frame members; leg frames supporting said U-shaped frame members; a bearing sleeve secured at the middle of each side frame member, said sleeves being in horizontal axial alignment; a pair of supporting standards; wheels supporting each standard; and a pivot stud projecting from each standard, said studs being adapted for insertion in said sleeves to rotatably support said frame members and said bed in a tilting position.

6. A trampolin as described in claim 5 having an arm member projecting from each standard and acting to prevent tilting of said frame members and bed in one direction; and a yoke device mounted on each standard adapted to receive said frame members when the latter are tilted

in the opposite direction to prevent withdrawal of said pivot studs from said bearing sleeves.
